UNITED STATES PATENT OFFICE.

EDUARD V. ASTEN, OF EUPEN, BELGIUM.

PAPER-MAKING MACHINE.

Application filed March 12, 1927, Serial No. 174,971, and in Germany November 11, 1926.

In paper making machines the drying of the paper web is effected by evaporating the moisture on the so-called drier part in which the paper web is conveyed by the aid of 5 drier felts over heated drying cylinders. A good drying can only be obtained if there exists a sufficiently large surface area at which the evaporation can take place. This surface is formed by the paper web itself and by 10 the drier felts which come into contact with the paper web and absorb moisture from the same. The moisture absorbed has to be evaporated again at the surface of the felts, which means that the felts have to be dried 15 in their turn. Owing to the construction of the paper making machines the vapors rising from the paper and felts can only draw off badly and large quantities of them remain hovering in the machine whereby, of course, 20 the process of evaporation is seriously impeded.

Now, the invention has for its object to provide the drier part of paper making machines with means by which hot air for drying 25 the paper web and felts is introduced into the machine in such a manner that it comes into contact with the surfaces of the paper and felts and at the same time carries the vapors out of the machine.

It would not be preferable to simply blow 30 hot air into the free spaces of the machine from one of its sides, because in that case the paper web would dry more quickly at the blowing-in side, i. e. it would not dry 35 uniformly. Besides, the hot air would choose the most open ways and would not come to the points where ventilation is worst.

According to the invention, rotating tubes 40 are mounted in the machine transversely thereof, these tubes being supplied with hot air and having in their walls slots through which the hot air flows out in a current which constantly changes its direction owing to the rotation of the tubes. The said slots are 45 preferably arranged in the tube walls on helical lines so that the air leaving the tubes will act like a feed screw and convey the vapors laterally out of the machine.

In paper making machines where the arrangement of special hot air tubes is not feasible because of a compact construction of the machine, the felt guide rollers are constructed as hot air tubes according to the invention.

The subject-matter of the invention is

illustrated by way of example in the accompanying drawing in which:

Fig. 1 is a diagrammatic side elevation of the dryer part of a paper making machine comprising special hot air tubes and 60 felt guide rollers constructed as hot air tubes.

Fig. 2 is a plan view of a hot air tube,

Fig. 3 is a similar view of a slightly modified tube, and

Fig. 4 is a longitudinal section through the tube shown in Fig. 2.

In Fig. 1, *a* are the drying cylinders, *b* is the paper web, *c* are the drier felts, *d* are rotary felt guide rollers which are constructed as hot air tubes, and *f* are special hot air tubes which are rotatably arranged in the transverse direction of the machine. The arrows show how the air currents leaving the hot air tubes flow against the surfaces of the 75 paper web and drier felts.

The hot air tubes *d*, *f* are provided with air outlet slots *e*. According to Fig. 2, these slots *e* are arranged on a line extending helically around the tube. In operation, the 80 hot air leaving the tube through the slots acts like a feed screw and carries the vapors away towards one side of the machine. This type of tube is to be used if it is intended to carry the vapors laterally away for protecting the attendants, who are assumed to be standing at the opposite side of the machine, against the heat and the vapors. The 85 said type of tube may also be used with advantage if it is intended to arrange at the particular side of the machine towards which the vapors are carried, a special drawing-off device for the vapors.

In the form of tube according to Fig. 3 the slots *e* are arranged on two helical lines 95 which extend from a common point in the transverse middle plane of the tube in opposite directions to the ends of the tube.

The supply of the hot air to the tubes *d*, *f* takes place at one end, as indicated at *x* 100 in Fig. 2-4, while the other end of the tubes is closed. When blowing air into a tube of the kind described, the pressure and velocity of the air will decrease in proportion to the number of air outlet slots. The pressure of 105 the air leaving the tube near the closed end will therefore be smaller than the pressure of the air leaving the tube in the neighbourhood of the air inlet end, which means that the ventilating action of the tube will not be 110

uniform. In order to overcome this drawback the tube is provided in its interior with a cone-shaped body *g*. The air will flow along the outer surface of the cone *g*. The cone causes a gradual reduction of the air space or sectional area of the tube towards the closed end of the tube. This gradual decrease of the sectional area of the tube is made to correspond with the increase of the area of the air slots *e* in the direction towards the closed end. It is thereby rendered possible to maintain the hot air at a substantially uniform pressure throughout the entire length of the tube and to produce a uniformly strong air motion throughout the width of the machine.

In many cases it will suffice to construct only the felt guide rollers as hot air tubes. New elements or machinery parts are then avoided and the rollers besides guiding the felts operate as hot air tubes. The rollers are heated and allow the hot air to enter into the spaces which are otherwise difficult to reach.

25 The fact that in operation some slots of the felt guide rollers are covered by the felts is of no importance, since a sufficiently large number of slots through which the air may flow out remains always uncovered.

30 Forming the felt guide rollers into hot air tubes of the kind described makes it possible to apply the invention without any difficulty to machines already existing.

The described tubes or rollers may also be used for drying other fibrous webs.

35 The means for properly mounting and rotating the tubes and supplying hot air to them may be of any suitable kind. For example, the tubes *f* may be driven from pulleys *h* on the shafts of the cylinders *a* through the medium of belts *i* cooperating with said pulleys *h* and with pulleys *k* on the tubes *f*.

Having thus described my invention, what I claim as new and desire to secure by Letters-Patent, is:—

1. In the drier part of a paper-making machine comprising drying cylinders and felts for conveying the paper web over these cylinders, rotary tubes mounted in the machine transversely thereof, one end of the tubes being open for the introduction of hot air into the tubes, air outlet slots arranged on helical lines in the cylinder walls of the tubes, and means in the tubes for gradually reducing the section of passage from the air inlet end towards the opposite end of the tubes.

2. In a drier part of a paper-making machine having drying cylinders and felts for conveying the paper web over these cylinders, tubes arranged in the free spaces be-

tween the paths of the paper web and felts, said tubes being formed with openings and adapted for the reception of hot air, and means for rotating the tubes to cause the hot air to flow out of said openings in a constantly changing direction, whereby such hot air currents impinge on the surfaces of the paper web and felts for drying the same and also remove the vapors accumulating in the machine.

3. A drier means cooperating with the drier part of paper-making machines, comprising hollow cylindrical bodies having a closed end and an open end, and arranged in the free spaces between the pairs of the paper web and felts in said drier part of the paper-making machine, the walls of the bodies being formed with openings spirally disposed axially of the bodies, the open ends of the bodies being adapted to be connected to a supply of hot air, and means for rotating the bodies to cause the hot air to pass through the openings in a stream following a convolute path and acting at all times in the same direction to dispel the vapors accumulating in the machine.

4. A drying means for the drier part of paper-making machines, comprising a tube closed at one end and open at the opposite end to a source of hot air supply, the wall of the tube being formed with openings, and means arranged interiorly of the tube to gradually reduce the cross-sectional area thereof open to the hot air current from the inlet end to the closed end of the tube.

5. A drying means for the drier part of paper-making machines, comprising a tube closed at one end and open at the opposite end to a source of hot air supply, the wall of the tube being formed with openings, and means arranged interiorly of the tube to gradually reduce the cross-sectional area thereof open to the hot air current from the inlet end to the closed end of the tube, the cross-sectional area reduction of the tube being in such proportion to the area of the openings as to maintain a substantially constant pressure of the hot air throughout the length of the tube.

6. In the drier part of a paper-making machine having drying cylinders, felts for conveying the paper web over the drying cylinders, guide rollers for the felts formed of hollow bodies closed at one end and open at the opposite end to a source of hot air supply, said bodies being formed with openings to discharge the hot air against the surface of the felts.

In testimony whereof I have signed my name to this specification.

EDUARD V. ASTEN.
